CLAIM

The ornamental design for a payment card enclosure, as shown and described.

DESCRIPTION

FIG. 1 is a perspective view of the payment card enclosure; FIG. 2 is a front view; FIG. 3 is a back view; FIG. 4 is a right side view; FIG. 5 is a left side view; FIG. 6 is a top view; and, FIG. 7 is a bottom view thereof.

The broken lines showing printed material are for the purpose of illustrating portions of the payment card enclosure and form no part of the claimed design.

1 Claim, 5 Drawing Sheets
